UNITED STATES PATENT OFFICE.

SAMUEL T. WORKMAN, JR., OF MOORESTOWN, NEW JERSEY.

MECHANICALLY-OPERATED TOY.

Application filed October 17, 1925. Serial No. 63,128.

This invention relates to mechanical toys and has for an object the provision of a toy which will represent a woman spanking a child, the construction and operation of

hold the outer end of the lever 15 raised, while a spring 24 which is connected to the arm 12 acts to yieldingly hold the arm 12 lowered. 60

5 the toy imitating the action of spanking and providing at each blow a sound in simulation of the cry of a child being spanked.

In the operation of the toy as thus far described, when the outer end of the lever 15 is forced downward, the brush 14 will be raised due to the upward pivotal movement

10 of the arm 12, the outer end of the arm 20 being positioned within the offset portion 22 of the slot 21. When the arm 12 is raised

65 to a proper height, the arm 20 will ride out of the offset portion 22, whereupon the spring 24 will pull the arm 12 downward so

15 that the brush 14 will strike the posterior portion of the figure 11. When the lever 15 is released, the spring 23 will return the arm 20 to its normal position within the offset portion 22 of the slot 21. 70

15 Another object of the invention is the provision of a toy of this character which in

20 addition to affording amusement when operated, is novel and attractive in appearance.

15 With the above and other objects in view, the invention further includes the following

novel features and details of construction,

25 to be hereinafter more fully described, illustrated in the accompanying drawings and

30 pointed out in the appended claims.

Figure 1 represents a perspective view of a toy constructed in accordance with the

20 invention.

Figure 2 is a perspective skeleton view showing the operating mechanism with the figures omitted.

The action above described will simulate the spanking of a child and to further add to the amusement of the device, the invention provides a sound producing element

25 which is actuated by the brush 14 striking

55 the figure 11. For this purpose there is pro-

vided a rubber ball or bag 25 which is positioned within the seat of the trousers of the

50 figure 11, the ball 25 being provided with a

55 wind operated sound producing element 26.

55

60 Referring to the drawings in detail where-

25 in like characters of reference denote cor-

65 responding parts, the reference character 10 indicates a seated figure, preferably a woman, while 11 represents a second figure, for example a child resting upon the lap of

30 the figure 10.

65

60 The figure 10 is provided with a movable right arm 12 and for this purpose the arm is pivotally secured to the shoulder being provided with an opening 13 for the recep-

75 tion of a suitable pivot. In addition, the

70 right hand of the figure 10 carries a hair

75 brush 14 which, when the arm is moved pivotally is arranged to strike the posterior portion of the figure 11.

75

80 For the purpose of operating the arm 12

80

85 there is provided an operating lever 15 which extends through a vertically disposed slot in the back of the figure 10, the slot being indicated by the dotted lines at 16 in Figure

85

90 2. The lever 15 is pivotally mounted within the figure at the point indicated at 17, while pivotally secured to the inner end of the lever is a rod 18. The rod 18 is slidable through a guide bracket 19 positioned within

90

95 the figure 10 and its upper end has extending therefrom a substantially right angled arm 20, the outer end of which enters an arcuate slot 21 provided in the arm 12. The lower

95

100 end of the slot is provided with an offset portion 22. A spring 23 which connects the arm 20 and the bracket 19 acts to yieldingly

100

105

110

110

a slot indicated by the dotted lines at 41 in Figure 2, is moved upward against the action of the spring 40 and as the upper end of the rod 39 is normally positioned within an offset portion 42 of the slot 36, this end of the arm 34 will be moved pivotally downward. The free end of the arm 27 will thus be moved upward and as the shoulder 29 is yieldingly held in the path 10 of the arm 27 by the weight 33, the end of the arm 27 will be seated upon the shoulder so that the ball or bag 25 will be fully expanded. The lever 15 is then actuated in the manner previously described and when 15 the descending brush 14 strikes the end 32 of the trigger 30, the said trigger will be moved pivotally to release the arm 27, whereupon the spring 43 will pull the arm 27 downward so as to squeeze the ball or bag 25 and operate the sound producing element 26.

The attractiveness of the toy may be increased by providing the representation of a jar of jam 44 and further representing 25 the features of the figure 11 as smeared with the jam.

The invention is susceptible of various changes in its form, proportions and minor details of construction and the right is 30 herein reserved to make such changes as properly fall within the scope of the appended claims.

Having described the invention what is claimed is:—

35 1. A toy comprising a seated figure, a second figure positioned thereon, a movable arm for the seated figure, yieldable means to resist movement of the arm in one direction and means to raise said arm and release the latter when in raised position to operate the arm to strike the second figure.

40 2. A toy comprising a seated figure, a second figure positioned thereon, a movable arm for the seated figure, means to raise the 45 arm and release the latter when in raised position to permit the arm to strike the second figure, a sound producing element and means controlled by the operation of the movable arm to actuate the sound producing element.

3. A toy comprising a seated figure, a second figure positioned thereon, a movable arm for the seated figure, means to raise the arm and release the latter when in raised position to permit the arm to strike the second figure, a sound producing element and means located in the path of the movable arm and actuated by contact of the latter to actuate the sound producing element.

4. A toy comprising a seated figure, a second figure positioned thereon, a movable arm for the seated figure, means to operate the arm to strike the second figure, a sound producing element, normally inactive means to operate the sound producing element, means to set the sound producing element operating means, means to hold said operating means in set position and means controlled by the operation of the movable arm 70 to release the holding means and actuate the sound producing element.

5. A toy comprising a seated figure, a second figure positioned thereon, a movable arm for the seated figure, means to operate 75 the arm to strike the second figure, a sound producing element, a spring actuated arm for operating the sound producing element, means to set the spring actuated arm, means to hold the arm in set position and means controlled by the operation of the movable arm of the figure to release the spring actuated arm.

6. A toy comprising a seated figure, a second figure positioned thereon, a movable arm for the seated figure, means to operate 85 the arm to strike the second figure, a sound producing element, a spring actuated arm for operating the sound producing element, a pivotally mounted trigger, means to move 90 the spring actuated arm to engage the trigger and hold said spring actuated arm in set position and means included in the trigger and arranged in the path of the movable arm of the figure to release the 95 spring actuated arm.

In testimony whereof I affix my signature.

SAMUEL T. WORKMAN, JR.
